UNITED STATES PATENT OFFICE.

DAVID FRANK HARTFORD, OF BOSTON, MASSACHUSETTS.

MACHINE FOR CUTTING SOLES.

SPECIFICATION forming part of Letters Patent No. 568,757, dated October 6, 1896.

Application filed December 14, 1894. Serial No. 531,768. (No model.)

To all whom it may concern:

Be it known that I, DAVID FRANK HARTFORD, of Boston, in the county of Suffolk and State of Massachusetts, have invented an Improved Machine for Cutting Soles and other Irregular Forms, of which the following is a specification, reference being had to the accompanying drawings, forming a part hereof, in which—

10 Figure 1 is a front elevation of one of my machines. Fig. 2 is a plan, and Fig. 3 a section, on line 33 of Fig. 2. Fig. 4 is a plan of certain of the parts, illustrating one feature of my invention and explained below. Figs. 15 5, 6, 8, and 10 illustrate the knife-carriage. Fig. 7 is a plan with certain of the parts removed, illustrating one feature of my invention and explained below. Fig. 9 is a detail illustrating the catch for the starting-lever, 20 as explained below.

My invention is an improved machine for cutting soles and other irregular forms from leather or other sheet material; and it consists, first, in novel means for moving the 25 knife-carriage about the form or pattern; secondly, in an additional adjustment of one or of both the supports for the pattern; thirdly, in a mechanism for varying the speed of the knife-carriage as it travels about the form, 30 and, fourthly, in a new combination of knife-holder and roller or tracer by which the knife is caused to cut a sole in accordance with the form.

In the drawings, A is a ring-gear supported 35 and guided by three rolls a, (best seen in Fig. 7,) the studs carrying these rollers being fast to the frame of the machine. The gear A is best made as a bevel-gear to mesh with the bevel-pinion a' on the main shaft a². By 40 making the gear A in the form of a ring and supporting it on rolls a, I provide room for the blocks b to support the table, which is, as usual, composed of two parts B B', each provided with a guide-strip b' b² to receive 45 the pattern-supports D D'. The carrier d' of the supports D D' also extend through the ring-gear A. These pattern-supports D D' are adjusted, as usual, nearer together or farther apart to suit the sizes of the pattern 50 of the sole to be cut, each being fast to its slide-block d' d², sliding between the guide-strips b' b² and the parts B B' of the table.

In machines of this class a table B B' and heel and toe supports D D', which form together a guide for the main rollers of the 55 knife-carriage, have long been known, and the knife-carriage has been carried about the pattern by a beveled gear and a belt or chain, as, for example, in my Patent No. 424,477, dated April 1, 1890; but by making the 60 gear A a ring and supporting it upon rollers a I make a much more compact and simple machine and greatly improve it, not only as to construction, but also as to operation and efficiency; and this is one feature of my invention. The supports D D' each carry a roller d², and the chain C, secured at one end to the box C' and at the other end to a coiled spring within the box C', extends about the rollers d², all substantially as in my patent 70 above referred to, so that no detailed description is here necessary. The box C' is fast, of course, to the ring-gear A, so that when ring-gear A is revolved the chain C compels the knife-carriage K to slide on table B B', the 75 main roller k of the knife-carrier being in contact with the guide-strips b' b², except when they move in the curved end slots formed by the periphery of the rollers d² and the curved wall of the slide-blocks d' d² of support D, or of support D', as will be clear to all skilled in the art, for the principle is the same as in other machines of this class, the difference being that I use a ring-gear A and thereby allow room for the supports b of table 80 B B' and for the carriers d d' of the supports D D' within that gear.

In order to cut different sizes of soles, the pattern-supports D D' must be adjustable, and it is desirable that both should be moved 90 simultaneously but in opposite directions. This is done in my improved machine by the lever d³ and links d⁴ d⁵, so that when lever d³ is moved in one direction on its fulcrum d⁶ (see Figs. 3, 4, and 7) link d⁴ will be pulled 95 and link d⁵ pushed, thereby moving carriers d and d' nearer together, a movement of lever d³ in the opposite direction pushing link d⁴ and pulling link d⁵ and thereby separating carriers d and d', and as the supports D D' move each with its carrier they are adjusted 100 for varying sizes or lengths of patterns. Heretofore the heel and toe pins g g', by which the form or pattern G is held, have been fixed,

respectively, to the supports D and D', and consequently the links d⁴ and d⁵ have both been plain links, but in my improved machine I fix the toe-pin g' to a carriage g², 5 which can slide on support D', and use an adjustable link d⁵ for moving carrier d' and support D', and it is the combination of the toe-pin g' with a carriage g² and an adjustable link d⁵ which constitutes the second feature 10 of my invention and enables the support D' to be adjusted after the form G is in place on the pins g g', so as to bring the axis of the roller d² on support D' in proper relation with the toe of the sole, and this is especially important 15 in that style of sole shown in Fig. 2 and in all soles whose toe part is narrow. The primary adjustment of the supports D and D', so that the pins g g' will receive the pattern G, is made by the proper movement 20 of the lever d³, substantially as in other machines of this class, but after that primary adjustment is made and the pins g and g' tied together by the pattern G the cam-lever d⁹ is turned to lengthen or shorten link d⁵ and move 25 carrier d' and support D' accordingly until the axis of roller d² of support D' is in proper relation to the toe of pattern G. In cutting soles this additional adjustment is necessary only at the toe; but with other patterns it 30 may be required at either or at both ends, and of course in such cases the link d⁴ should be adjustable, as is the link d⁵; but this feature of my invention is the additional adjustment of the pattern-support and may obviously 35 be used for either one or for both of the pattern-supports.

In order to start the machine, the operator presses down upon the hand-lever H¹, and the first effect of that pressure is to throw 40 the latch end of lever H over lever H, while the next effect is to force levers H, H¹, and H² downward, and as lever H² is fast to rock-shaft h⁴ that rock-shaft is turned in a direction to pull on rod h⁵ and thus force clutch 45 member h² against h', compressing spring h¹⁰, while the end of lever H is moved out of the path of trip h and lever H² is locked by lever H³. This motion of rock-shaft h⁴ also brings its small end against the hooked end of lever 50 j³ and makes it certain that lever j³ is brought into position to unlatch the clutch members j⁶ j⁷, which are held unclutched by the spring-latch j' catching on lever j³, so that the machine is driven at speed by the direct engagement of h² with h'; but when trip J, fast to 55 gear A, strikes the dog fast to lever j that lever is moved far enough to unlatch j', and lever j³ is moved on its fulcrum by the spring on rod j⁴, and as rod j⁴ carries with it not only lever j³, but also clutch member j⁶, as will be clear from Fig. 2, the action of trip J on lever j connects the clutch members j⁶ and j⁷; but when lever j is thus moved by trip J it also moves lever H endwise far 60 enough to trip lever H³ and release lever H², thereby unclutching h' and h², but not ap-

plying brake N. When j⁶ j⁷ are clutched and h' h² unclutched, the speed of the machine is greatly reduced, for member h² then drives, through sprocket S, member j⁶, member j⁸ 70 drives member j⁷, and member j⁷ drives member h' through sprocket S', and the speed of member h' and of shaft a², fast to member h', is much less than when shaft a² is driven by contact of members h' and h². This slow 75 speed continues until members j⁶ and j⁷ are separated and members h' and h² brought into contact, so that when trip J is properly adjusted the movement of the knife about the toe is so slow that a pointed toe can be 80 cut. This automatic mechanism for decreasing the speed of the knife-carriage as it travels about the form may of course be made to operate at any part of the form by adjusting trip J. This feature of my invention is not 85 herein claimed, as it forms the subject-matter of another application, Serial No. 581,599, filed March 2, 1896.

After the machine is slowed down by the operation of lever j it may be stopped by 90 putting lever j³ into the position shown in Fig. 2, which will unclutch j⁶ j⁷ and stop the machine. When the machine is in operation at full speed, lever H² is depressed and locked by lever H³, but lever H is brought 95 back to place by the spring on its outer end, as clearly shown in Fig. 2.

The knife-carriage consists of two main parts, one of which, K, is connected to the chain C and is guided by the rollers k, which 100 travel against the inner faces of the guide-strips b' b² and about the roller d² as gear A revolves, the bottom of the part K resting and sliding upon the table B B', (see Figs. 5, 6, and 8,) and all this is too well known to 105 need further description. On this bed K is fixed a headed stud k', held by a set-screw k² and connecting link k³ with bed K. The link k³ is pinned to the outer end of plunger or ram k⁴; and ram k⁴ is pinned to lever 110 k⁵, the short arm of which lever is connected by rod k⁶ to spring k⁷, rod k⁶ passing through the abutment of spring k⁷, which abutment is a shelf fast to bed K. The purpose of these devices is to press the ram k⁴ endwise by the force of spring k⁷, and also to give the ram k⁴ an easy motion endwise and without confining the ram in a groove, thereby 115 guiding the ram so that the path over which the knife-edge moves shall be a straight line, 120 and yet not cramping the ram by confining it in a groove; and mounting the ram in this way is one feature of my invention.

In order to retract ram k⁴ the lever k⁸ is turned on its fulcrum and through link k⁹ 125 moves lever k⁵ on its fulcrum, thereby compressing spring k⁷, as well as retracting ram k⁴, and lever k⁸ brings up on stop k¹⁰, as indicated by the dotted lines in Fig. 5.

In the inner end of ram k⁴ the pin m is secured, and the lower part m' of swivel-head m' m² swivels on pin m. This lower part m'

is connected to the upper part m^2 by the screw m^3 , thus making the two parts m' and m^2 practically one part held to ram k^4 by the pin m . The upper part m^2 carries a block on its 5 upper surface, on which block the knife-holder m^4 is placed and to which it is secured.

The tracing-roller M is mounted upon the three wheels n n' n^2 , which are pinned to the swivel-head. The purpose and effect of this 10 arrangement is to bring the strain of the tracing-roller on the swivel-head nearer the swivel-pin m , for if the tracing-roller were held to the swivel-head by a journal at the center of the tracing-roller that journal 15 would necessarily be farther from the swivel-pin; for, practically, the pin which receives the strain of the tracing-roller and connects it with the swivel-head (shown in Fig. 6 as coincident with axis of screw m^3) must be 20 about as close to the axis of the swivel-pin m as is the axis of the wheel n , and if the tracing-roller were connected to the swivel-head by a single journal, that journal would 25 be much farther than is desirable from the swivel-pin.

The operation is as follows: The pattern G is placed upon the pattern-studs g and g' , the supports D and D' having been adjusted to receive it, and the support D' is adjusted to 30 bring the axis of its roller d^2 in proper relation with the sole when the shape of the sole requires that adjustment. The lower clamp is then put in place and the stock put on and clamped, all as usual and as will be clear 35 from Fig. 1. Hand-lever H' is then depressed, carrying with it lever H and lever H^2 and clutching h' and h^2 , and the machine starts, and lever H rises as soon as trip h gets out 40 of the way, while lever H^2 is locked in its depressed position by the lower end of lever H^3 so long as the machine remains at full speed, that is, until trip J actuates lever j , unclutching h' and h^2 and clutching j^6 and j^7 , as above 45 described; but when the knife has been carried by the toe at the slow speed the attendant again depresses levers H , H' , and H^2 , and H^2 is locked in its depressed position by lever H^3 until trip h moves lever H endwise, thereby unlocking lever H^2 and unclutching 50 h' and h^2 , as before described, also at the same time applying brake N and slightly distending spring h^7 , so that the knife is carried slightly past the point where it commenced to cut and then retracted against stop-lever 55 h^8 , so that the knife is left in its proper position for the next operation in spite of the

fact that it has been carried past that position to fully complete the cut.

The machine can be stopped by hand when at slow speed by moving lever j^3 and when at 60 full speed by moving lever H^3 .

In Figs. 5, 6, and 8 I have shown the knife k supported in a holder m^4 , which consists of a base with an arm extending from it and engaging with the upper end of the knife k . 65

In cutting soles from the blanks it is important to support the knife k at both ends, and this double support of the knife in machines of this class is an important feature of my invention. The knife-holder proper is the 70 base m^4 , and the lower end of the knife is clamped in that base in the usual way; but I have added the arm m^5 , in which the upper end of the knife is also clamped, and I have made this arm detachable, as it is in the way 75 in cutting from the strip or race.

What I claim as my invention is—

1. In a machine for cutting forms the combination of a ring-gear; studs and wheels within that gear for supporting it; blocks 80 within that gear for supporting the table of the machine; that table; pattern-supports also within that gear; a pattern carried by these supports; a knife-carriage on the table, and a connection between the ring-gear and 85 the knife-carriage; all substantially as described.

2. In a machine for cutting forms the pattern-supports, in combination with means for adjusting both to receive the pattern, and additional means for further adjusting one of them to suit an angle or quick curve of the pattern, all substantially as described. 90

3. In a machine for cutting irregular forms a knife-carriage consisting of a bed; an endwise-moving plunger or ram; a swivel-head, connected by a pin to one end of the ram; a knife-holder on the swivel-head; and two links k^3 and k^5 to connect the plunger and bed and guide the plunger in its endwise movements; all substantially as described. 95

4. In combination a swivel-head; a knife carried by it; a pin on which the swivel-head swivels; a ring-tracing roller; and wheels mounted on the swivel-head, and supporting 100 the ring-tracing roller; all substantially as set forth. 105

DAVID FRANK HARTFORD.
